BRAKE HANGER WEAR PLATE

Frederic Schaefer, Pittsburgh, Pa.

Application April 26, 1944, Serial No. 532,788

14 Claims. (Cl. 188—209)

This invention relates to wear plates for the brake hanger brackets of railway car brake rigging.

A brake hanger bracket is usually a U-shape or jaw-like member having spaced top and bottom walls connected at one end by a vertical end wall. One type of wear plate inserted in such brackets to provide a bearing for a brake hanger is made from a plate bent into U-shape to produce vertically spaced walls that engage the top and bottom walls of the bracket. Due to the brackets being rough castings in which the opposite walls may not be parallel transversely, the wear plates often do not fit snugly against those walls. This permits the wear plates to vibrate and shake around in the brackets so that the engaging surfaces are worn excessively.

It is among the objects of this invention to provide a wear plate which will seat tightly in brackets regardless of inaccuracies in their shape, which will take up any wear as it occurs, and which, although made by assembling several different elements, is permanently bound together as a unit.

In accordance with this invention the wear plate is formed from a base member provided with a brake hanger seat above which there is a cover member that is engaged by the hanger when it is under compression. These two members are loosely connected together so that they can accommodate themselves to irregularly shaped brackets. To hold the base and cover tightly against the opposite walls of a bracket, resilient means is provided for pressing the two members apart. Preferably, this means includes one or more coil springs compressed between the base and cover. Most suitably, the base member is provided with a socket for receiving the spring the upper end of which bears against the cover. The cover preferably is universally movable relative to the base member to which it may be loosely but permanently connected at one end.

The preferred embodiment of the invention is illustrated in the accompanying drawing in which Fig. 1 is a plan view of my wear plate with the cover member partly broken away; Fig. 2 is a side view thereof showing a brake hanger bracket in broken lines; and Fig. 3 is a reduced front view of the wear plate taken on the line III—III of Fig. 1 to show half of it in section.

Referring to the drawing, this wear plate has two main parts; namely, a base member 1 and a cover member 2. The base member is formed for seating in the usual manner on the lower wall of a brake hanger bracket 3 indicated in broken lines in Figs. 2 and 3. The inner end of the base is provided with a concave seat 4 extending across it for receiving the upper yoke 6 of a brake hanger, also indicated in broken lines in the same two figures. Directly in front of this seat the base is increased in thickness considerably and is pro-

vided near its opposite sides with a pair of downwardly extending sockets 7. In each of these sockets there is a coil spring 8 that projects a short distance above it. The front wall of the base curves inwardly or rearwardly between the two sockets to form a recess 9 for receiving a vertical fastening member, such as a cotter pin 11, that holds the wear plate in the hanger bracket. Because of the relatively great height of the wall 10 of the recess, the fastener has a considerable area of contact with the wear plate and therefore they will not wear each other appreciably.

The cover member 2 has its inner end disposed above the hanger and its seat 4 to serve as a bearing surface when the brake hanger is under compression and consequently raised off its seat on the base member. The cover extends outwardly across the tops of the two coil springs which engage its lower surface, and beyond the front of the base member. The central part of the cover is provided with an opening 15 in alignment with recess 9 in the base to permit fastener 11 to extend through the cover.

It is a feature of this invention that this wear plate can accommodate and fit itself to brackets in which the upper and lower walls are not parallel to each other transversely. Accordingly, the cover is loosely connected to the base so that it can float, i. e., move universally relative to the base. For this purpose, the cover preferably is loosely hinged to the front end of the base. Thus, the base may be provided with a forwardly projecting stirrup 16 integrally connected to the upper ends of the two sockets and spaced forwardly of recess 9. The front end of the cover is provided with an integral extension 17 that hooks under the stirrup. That is, as shown in Fig. 2, this extension extends down in front of the stirrup, back under it, and then up behind it.

40 The hooked portion thus formed does not tightly grip the stirrup, but is loose enough to permit the cover to float on the base member. In order to prevent the cover and base from accidentally coming apart when the wear plate is not in use, 45 cover extension 17 extends up behind the stirrup far enough to leave a space between its upper end and the bottom of the cover that is less than the thickness of the stirrup. The stirrup can not pass through this restricted space, so the cover 50 can not escape from the base member. The cover extension hook engages the stirrup sufficiently, however, to prevent the cover from swinging upwardly far enough to allow the springs to escape from their sockets.

55 When this wear plate is driven into bracket 3 the cover and base are forced toward each other against the resistance of the two coil springs 8 which are thereby compressed. If the upper and lower walls of the bracket do not happen to be 60 parallel transversely, one of the springs will be compressed more than the other, but they will

force the base and cover to seat tightly against the bracket walls that they engage. The wear plate thus fits snugly in the bracket, whereby a great deal of unnecessary wear is eliminated.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A wear plate for use in a railway car brake hanger bracket, said plate comprising a base member provided with a brake hanger seat, a cover member above said seat and loosely connected to said base for universal movement relative thereto, and separate resilient means pressing said members apart.

2. A wear plate for use in a railway car brake hanger bracket, said plate comprising a base member provided with a brake hanger seat, a cover member above said seat and loosely connected to said base, and a pair of springs carried by said base in transversely spaced locations, said springs pressing against the lower surface of said cover near its opposite side edges.

3. A wear plate for use in a railway car brake hanger bracket, said plate comprising a base member provided with a brake hanger seat, a cover member above said seat and loosely locked to said base or universal movement relative thereto, and separate resilient means pressing said cover upwardly.

4. A wear plate for use in a railway car brake hanger bracket, said plate comprising a base member provided with a brake hanger seat, a cover member above said seat and loosely locked to said base at one end, whereby to render the cover universally movable relative to the base, and a pair of laterally spaced springs compressed between said base and cover.

5. A wear plate for use in a railway car brake hanger bracket, said plate comprising a base member provided with a brake hanger seat, a cover member above said seat and loosely connected to said base, said base being provided in transversely spaced locations below the cover with downwardly extending sockets, and coil springs mounted in said sockets and pressing upwardly against the bottom of the cover.

6. A wear plate for use in a railway car brake hanger bracket, said plate comprising a base member provided with a brake hanger seat, a cover member above said seat and loosely connected to said base, said base being provided in transversely spaced locations below the cover with downwardly extending sockets, and coil springs mounted in said sockets and pressing upwardly against the bottom of the cover, said cover and base being provided between said sockets with vertically aligned openings for receiving a bracket attaching member.

7. A wear plate for use in a railway car brake hanger bracket, said plate comprising a base member provided with a brake hanger seat, a cover member above said seat and loosely connected to said base, said base being provided in transversely spaced locations below the cover with downwardly extending sockets, and coil springs mounted in said sockets and pressing upwardly against the bottom of the cover, said cover and base being provided between said sockets with vertically aligned openings for receiving a

bracket attaching member, the opening through the base having high rear and side walls and the front of said opening being unrestricted for most of its height.

8. A wear plate for use in a railway car brake hanger bracket, said plate comprising a base member provided with a brake hanger seat, a universally movable cover member above said seat, resilient means pressing said cover upwardly, and means for limiting movement of the cover away from the base.

9. A wear plate for use in a railway car brake hanger bracket, said plate comprising a base member provided with a brake hanger seat, the upper portion of the base being provided at one end with a stirrup, a cover member above said seat and having one end hooked under said stirrup, and resilient means pressing said cover upwardly.

10. A wear plate for use in a railway car brake hanger bracket, said plate comprising a base member provided with a brake hanger seat, the upper portion of the base being provided at one end with a stirrup, a cover member above said seat and having one end hooked under said stirrup to provide a hinge connection between the base and cover, and a spring carried by the base and pressing upwardly against the cover.

11. A wear plate for use in a railway car brake hanger bracket, said plate comprising a base member provided with a brake hanger seat at one end and an outwardly projecting stirrup at the other end, a cover member above said seat and having an extension extending down one side of the stirrup and up the other side to provide a loose connection between cover and base, and resilient means pressing said cover upwardly.

12. A wear plate for use in a railway car brake hanger bracket, said plate comprising a base member provided with a brake hanger seat at one end and an outwardly projecting stirrup at the other end, a cover member above said seat and having an extension extending down the outside of the stirrup and up the inside of it to a point spaced from the bottom of the cover a distance less than the thickness of the stirrup, whereby the cover is locked to the stirrup, and resilient means for pressing the cover upwardly.

13. A wear plate for use in a railway car brake hanger bracket, said plate comprising a base member provided with a brake hanger seat at one end, the opposite end of the base having a high wall provided centrally with a vertically extending recess adapted to receive a bracket fastener, the upper part of said wall on opposite sides of said recess being connected by an outwardly projecting stirrup, a cover member above said seat and having an extension loosely hooked under said stirrup, said cover being provided with a vertical fastener-receiving opening above said recess, and a spring compressed between said base and cover for urging the cover upwardly.

14. A wear plate for use in a railway car brake hanger bracket, said plate comprising a base member provided with a brake hanger seat at one end, the opposite end of the base being provided with a pair of transversely spaced vertical sockets, an outwardly projecting stirrup integrally connected at its ends to the upper end of the socket walls, a cover member above said seat and hinged at one end to the stirrup, and coil springs disposed in said sockets and pressing upwardly against the bottom of the cover.
